(57) CLAIM

The ornamental design for a head wrap for covering dred-locks, as shown and described.

DESCRIPTION

FIG. 1 is a front elevational view of a head wrap for covering dred-locks showing my new design;

FIG. 2 is a side elevational view thereof;

FIG. 3 is a top plan view thereof;

FIG. 4 is a bottom plan view thereof; and,

FIG. 5 is a side elevational view positioned on a user's head thereof.

The broken line showing of the head is for illustrative purposes only and forms no part of the claimed design.
